DESIGN FOR A DISPLAY DEVICE

Virginia K. Campbell, Evanston, Ill.

Application April 16, 1945, Serial No. 119,037

Term of patent 14 years

(Cl. D80—9)

To all whom it may concern:

Be it known that I, Virginia K. Campbell, a citizen of the United States, residing at Evanston, in the county of Cook and State of Illinois, have invented a new, original, and ornamental Design for a Display Device, of which the following is a specification, reference being had to the accompanying drawing, forming a part thereof.

The figure is a front elevation of a display device showing my new design.

I claim:

The ornamental design for a display device, as shown.

VIRGINIA K. CAMPBELL.
